UNITED STATES PATENT OFFICE.

WILLIAM E. COLE, OF MONTGOMERY, ALABAMA.

BRICK-DRIER.

SPECIFICATION forming part of Letters Patent No. 378,237, dated February 21, 1888

Application filed August 16, 1887. Serial No. 247,082. (No model.)

To all whom it may concern:

Be it known that I, WILLIAM E. COLE, a citizen of the United States, residing at Montgomery, in the county of Montgomery and State of Alabama, have invented certain new and useful Improvements in Brick-Driers, of which the following is a specification, reference being had therein to the accompanying drawings.

10 My invention relates to driers for evaporating the moisture of bricks and other material; and the objects of my improvement are to produce a drier that is inexpensive to build and inexpensive to operate. I accomplish these objects by the construction illustrated in the accompanying drawings, and particularly set forth in the claim.

In the drawings, Figure 1 is a longitudinal vertical section of a drier constructed in accordance with my invention. Fig. 2 is a transverse vertical section of the same. Fig. 3 is a plan view of a portion of the floor of the same, partly broken away to show its internal supports and spaces between them.

25 In said drawings, A represents the foundation of the apparatus, that may be simply the ground upon which it rests, and upon said ground is placed a close-fitting floor, a, either of wood, cement, concrete, &c., to keep air and moisture from entering the bottom of the apparatus through its foundation. Upon the floor a are placed a series of props, a², about three inches square and one or two inches high, upon which is placed the steam-tight 30 hollow floor B, that may be from five to eight feet wide and a hundred feet long, more or less. The floor is in the form of a shallow rectangular box, about an inch deep, having a sheet-metal top, b, and a sheet-metal bottom, b², 35 either riveted together at their edges or nailed to a wood parting-strip, b³, placed adjacent to said edges to keep the top and bottom sheets, b b², at a proper distance apart. Suitable packing is placed between the edges of the 40 plates, or between them and the strips b³, to render the box-floor steam-tight when its edges are secured.

Upon the box-floor B are placed the rails C of a track to carry a series of cars, D, the floor 45 of which is made of slats having their ends united by a frame to permit hot air to ascend

through and among the bricks or other material placed upon said cars. Within the box-floor are also placed a series of parting-blocks, b⁴, at points under the rails C, to support said rails and the weight placed upon them; but said blocks are at such distances apart as not to interfere with the circulation of steam in any direction in the box-floor. A pipe, d, is inserted at one end of the floor to admit steam 60 therein either from the exhaust-pipe of an engine or live steam direct from the boiler in the night-time when the engine is at rest. The box-floor is slightly inclined downward at the rear end to direct to that end the water 65 resulting from the condensation of steam, and said water is carried off through a pipe, d², provided with a regulating-cock, d³. A trap, d⁴, is placed upon said pipe, to prevent the escape of steam under a slight pressure, and the 70 cock d³ permits its escape to be regulated.

The box-floor is inclosed in a building, E, having doors F at each end for the passage of the cars D. It has also a ceiling, E², to concentrate the heated air at as low a level as 75 possible, and in said ceiling there is an opening leading into the uptake-flue G, located over the front end of the drier.

When the drier is in use, cars loaded with fresh bricks or other material to be dried are 80 rolled in over the box-floor. The end doors, F, are then closed and steam is admitted within said box-floor. The top and bottom sheets, b b², thereof becoming highly heated, a strong draft is produced in the uptake-flue G. Air 85 is admitted into the drier from the shallow flue a² under the box-floor. It enters at the front end, where a valve or door, a¹, is placed to regulate its admission, and passes under the whole length of the box-floor B, and, being in 90 contact therewith, is highly heated and ascends against the rear end of the box-floor, and enters the drying-room under the floor of the cars. A small portion of the air ascends through the openings in the slatted floor of the 95 rear car, and the balance of the heated air, with the heated air ascending from the surface sheet b of the box-floor, passes through the interstices in all the other cars in the drier and ascends to the ceiling and the uptake-flue G, 100 with the moisture it has collected from the material on the cars.

Having now fully described my invention, I claim—

In combination with a chamber having an uptake-flue at one end and a substantially air-tight floor, a series of props upon said floor, and upon said props a box-floor having a sheet-metal top and bottom, parting-blocks between them, a steam-admitting pipe at one end and an escape at the other, and an air-flue

under substantially the whole of said box-floor, to substantially as and for the purpose described.

In testimony whereof I affix my signature in presence of two witnesses.

WILLIAM E. COLE.
